CLAIM

The ornamental design for a television receiver, as shown and described.

DESCRIPTION

1. Television receiver

1.1 : Perspective

1.2 : Front

1.3 : Back

1.4 : Left

1.5 : Right

1.6 : Top

1.7 : Bottom

1.8 : Perspective

1.9 : Front

1.10 : Back

1.11 : Left

1.12 : Right

1.13 : Top

1.14 : Bottom

1.15 : Perspective

1.16 : Front

1.17 : Back

1.18 : Left

1.19 : Right

1.20 : Top

1.21 : Bottom

Figures 1.1-1.21 show one (1) design. The subject design is characterized by a rollable display. Figures 1.1-1.7 show the unused state of the subject design with the display unit rolled and unexposed. Figures 1.8-1.14 show an intermediate state of the subject design with the display unit partially exposed. Figures 1.15-1.21 show the use state of the subject design with the display unit fully exposed.

(Continued)

The broken lines shown are included for the purpose of illustrating portions of the article and form no part of the claimed design.
